VENETIAN BLIND BRACKET

Harry Nelson, New York, N. Y., assignor to
 Lorentzen Hardware Mfg. Corp., New York,
 N. Y., a corporation of New York

Application June 4, 1946, Serial No. 674,265

12 Claims. (Cl. 248—264)

1

This invention relates to Venetian blinds, and more particularly to a so-called installation bracket for removably supporting the blind in position adjacent to a window or door.

A Venetian blind is essentially an assembly of superimposed slats, so suspended and articulated together that the assembly can be collapsed and extended to raise and lower the blind, and that the slats can be tilted to vary the light openings between them. Usually the assembly of slats is suspended from a head-bar on which is mounted the elevating and tilting mechanism. This arrangement permits installation and removal of the blind as a unit; and the usual practice is to removably support the ends of the head-bar on so-called installation brackets which have been secured to the window jamb.

Various forms of installation brackets are now in use. Some of them are quite satisfactory, particularly certain brackets used for supporting conventional wooden head-bars. However, certain limitations and disadvantages inhere in the installation brackets heretofore used for so-called inclosed metal heads, such as "heads" being metal head-bars which are hollow and which inclose the elevating and tilting mechanism of the blind.

The general object of the present invention is to provide an improved installation bracket for inclosed head-bars, which can be economically manufactured on a quantity production basis.

Among other objects of the invention are the provision of such a bracket having a reduced number of parts, which can be conveniently manipulated for installing the head-bar, which securely retains the head-bar, which can be easily and conveniently manipulated to release the head-bar, which is adapted for mounting on either the front or the side of the jamb of a window frame, which neatly receives the head-bar without unsightly gaps, and which is composed of parts adapted for manufacture by stamping from sheet metal.

My invention is clearly defined in the appended claims. In the claims, as well as in the description, parts are at times identified by specific names for clarity and convenience, but such nomenclature is to be understood as having the broadest meaning consistent with the context and with the concept of my invention as distinguished from the pertinent prior art. The best form in which I have contemplated applying my invention is illustrated in the ac-

2

companying drawings forming part of this specification, in which:

Fig. 1 is an isometric view of the bracket, viewed from one side, with the retainer open;

5 Fig. 2 is an isometric view of the bracket, viewed from the opposite side, with the retainer open;

Fig. 3 is a front elevation of the bracket, with the retainer closed;

10 Fig. 4 is a top plan view, partially in section, with the retainer closed;

Fig. 5 is a left side elevation, with the retainer closed;

15 Fig. 6 is a right side elevation, with the retainer closed;

Fig. 7 is an isometric view of a fragment of the retainer showing the pivoted end thereof;

Fig. 8 is a detail sectional view taken on the line 8—8 of Fig. 7;

20 Fig. 9 is an enlarged fragmentary side elevation of the upper right-hand corner portion of the bracket, showing the retainer in partly opened position;

Fig. 10 is a view similar to Fig. 9, showing the retainer in fully opened position;

Fig. 11 is an enlarged fragmentary side elevation of the lower right-hand corner portion of the bracket, showing the retainer in nearly closed position;

30 Fig. 12 is a view similar to Fig. 11, showing the retainer in fully closed position; and

Fig. 13 is a view similar to Fig. 7, showing a modified retainer.

The brackets are made and used in pairs, one bracket for the left-hand end of the head-bar, and one for the right-hand end of the head-bar. The bracket shown is for the left-hand end of the head-bar, and it will be understood that the other bracket of the pair is of the same construction but of opposite hand.

The bracket consists of three parts, which for convenience will be called the body, the retainer, and the pivot. The body, which is designated as a whole by 15, is a one-piece sheet metal stamping. The retainer, which is designated as a whole by 16, is also a one-piece sheet metal stamping. The pivot 17 is a suitable conventional rivet, which may be a hollow-ended rivet.

50 The body 15 includes a flat plate 18 from which project a horizontal marginal flange 19 and a vertical marginal flange 20. Flange 19 is adapted to receive and support one end of the head-bar. Plate 18 is provided with holes 21, 21 to receive screws for securing the bracket

to the side of a window jamb; and flange 20 is provided with holes 22, 22 to receive screws for securing the bracket to the front of a window jamb. Between holes 22, 22 a filler 24 is pressed forwardly a distance equal to the thickness of the head of a round-headed screw such as would sometimes be used for securing the flange 20 to the front of the window jamb. When the bracket is mounted on the side of a jamb, there are no screw heads at holes 22, 22 and the filler 24 then acts as a stop to correctly position the rear face of the head-bar.

The retainer 16 has a flange 25 pivoted at 17 to the upper right-hand corner of the plate 18. Extending perpendicularly to flange 25 is a flange 26 which, when the retainer is closed, engages the front face of the head-bar and thereby retains the head-bar on the bracket. This flange may be transversely corrugated to nest with fluting on the front of the head-bar, such as the fluting shown in my copending application Serial No. 601,671, filed June 26, 1945, now Patent No. 2,455,185.

The pivot pin 17 occupies a fixed position in plate 18 and passes through a slightly arcuate slot 27 in retainer flange 25, the slot being disposed as shown. This pin-and-slot connection allows the retainer 16 to move forwardly as it is swung into open position. The retainer is provided with a laterally extending finger 28, and as the retainer approaches open position (see Fig. 9), this finger strikes an incline 29 which is formed on the upper edge of plate 18. As opening movement is continued, the retainer 16 rocks about finger 28 and the finger slides down incline 29 until the fully open position is reached; see Figs. 10, 1 and 2. This rocking movement about finger 28 provides strong leverage tending to slide the retainer 16 forwardly on pin 17. This forward movement is utilized in frictionally clamping the retainer in open position, as will now be pointed out.

As shown in Figs. 7 and 8, the retainer flange 25 is provided adjacent to the slot 27 with a zone 30 which is pressed laterally away from plate 18. When portion 27a of slot 27 engages the rivet 17, the retainer 16 swings freely. However, as the retainer shifts forwardly, under the rocking action of finger 28 on incline 29, portion 27b of the slot engages the rivet and increasing wedging or clamping pressure is applied between the head of rivet 17 and the plate 18. This holds the retainer in open position. With the retainers of both brackets held in open position, one man can readily put the head-bar in place, having both hands free to handle the blind. By introducing a narrow band of severance s as shown in Fig. 13, zone 30 is subdivided into two resilient portions 30a and 30b which improve the holding action in retainer-open position.

Referring more particularly to Figs. 11 and 12, the free end of the retainer 16 is formed with a springy integral latching tongue 31 having a rounded nose portion 32. As the retainer is moved into closed position, the nose engages the forward portion of flange 19 and the tongue is thereby flexed upwardly. In fully closed position the nose 32 snaps into a rectangular hole 34 in flange 19 and holds the retainer closed. The hole 34 lies close against plate 18. By so stamping this hole that it will extend a short distance up plate 18 as shown, proper clearance for the latching tongue is insured and visual inspection of the latching hole is facilitated. As shown more particularly in Figs. 4 and 1, the forward

edge of flange 19 is rectangularly cut away at 35, so that a screw driver or similar instrument usable as a lever can be inserted from beneath to pry the closed retainer into unlatched position.

Fig. 3 shows in greatly exaggerated degree how the forward edge of plate 18 may be bowed to cause the flange 25 of retainer 16 to hug the plate 18. When rivet 17 is set, it tends to so dispose the retainer as to cause flange 25 thereof to extend along the line x—y. Of course the bowing of plate 18 is, in practice, kept so small that the retainer can be readily closed under the flexibility and looseness of parts which exist. However, the bowing of the front edge of the plate biases the lower end of the retainer toward plate 18, thereby causing the retainer flange 25 to hug the plate despite a measure of looseness or loosening of the rivet 17. This not only insures a slight appearance, but maintains the retainer in proper lateral position for engagement of latch 31 with hole 34.

It will be seen that the bracket is exceedingly simple, being composed of two sheet metal stampings and a rivet. The retainer hugs plate 18, and filler 24 insures that there will be no appreciable gap between flange 16 and the forward face of the head-bar. The arrangement of retainer 16, including its pin-and-slot connection, is such that it can be readily opened and closed, even when mounted on the side of a jamb very close to the top of the window frame, and even when the head-bar extends substantially the full height of plate 18.

I claim:

1. A bracket for supporting a Venetian blind, said bracket comprising: a plate having a projecting lower flange adapted to support the head-bar of a Venetian blind, and a retainer swingably mounted adjacent to the upper front corner of said plate for retaining a Venetian blind head-bar on said lower flange, said retainer having an inwardly-directed flange overlapping said plate in parallel relation when the retainer is in closed position, and said inwardly-directed flange having a slot extending substantially across the lower portion thereof, forming a relatively long, narrow, resilient latching tongue at the bottom of said retainer adapted to engage said lower flange when said retainer is in closed position.

2. A bracket for supporting a Venetian blind, said bracket comprising: a relatively flat plate having a projecting lower flange adapted to support the head-bar of a Venetian blind, and a retainer swingably mounted adjacent to the top front corner of said plate for retaining a Venetian blind head-bar on said flange, said mounting comprising a pivot secured to one of said members and passing through a slot in said other member, and an extension at the top of said retainer overlying the upper front corner portion of said plate and adapted to engage said plate portion upon swinging movement of said retainer and thereby cause relative linear movement between said pivot and said slot.

3. A bracket for supporting a Venetian blind, said bracket comprising: a relatively flat plate having a projecting lower flange adapted to support the head-bar of a Venetian blind, a retainer for retaining a Venetian blind head-bar on said lower flange, and a pivot secured adjacent to a front corner portion of said plate and swingably mounting said retainer thereon, said pivot passing through a slot in said retainer, and a lateral extension on the retainer adjacent to the pivot

and adapted to engage said front corner portion of said plate upon pivoting movement of said retainer and thereby cause relative linear movement between said pivot and said slot.

4. A bracket for supporting a Venetian blind, said bracket comprising: a relatively flat plate having a projecting lower flange adapted to support the head-bar of a Venetian blind, and a retainer swingably mounted adjacent to the top front corner of said plate for retaining a Venetian blind head-bar on said lower flange, said mounting comprising a pivot secured to one of said members and passing through a slot in the other of said members, material near one end of said slot being adapted to frictionally engage the other member upon sliding movement to dispose said pivot at said slot end, and an extension at the top portion of said retainer overlying the upper front corner portion of said plate and adapted to engage said plate portion upon swinging movement of said retainer whereby relative sliding movement to dispose said pivot at said slot end is effected upon movement of said retainer to open position.

5. A bracket for supporting a Venetian blind, said bracket comprising: a relatively flat plate having a projecting lower flange adapted to support the head-bar of a Venetian blind, and a retainer having a laterally-projecting flange for retaining a Venetian blind head-bar on said lower flange and having an inwardly-directed flange overlapping said plate in parallel relation when the retainer is in closed position, said retainer being swingably mounted adjacent to the upper front corner of said plate and said inwardly-directed flange being provided at a lower position thereon with a latch formation for latching the retainer in closed position, that portion of the front edge of said lower flange which is adjacent to said inwardly-directed flange being spaced from the laterally-projecting retainer flange when the retainer is closed thereby providing a space for the reception of a lever to aid in unlatching said retainer.

6. A bracket for supporting a Venetian blind, said bracket comprising: a relatively flat plate having a projecting lower flange adapted to support the head-bar of a Venetian blind, and a retainer having one end swingably mounted adjacent to a front corner of said plate for retaining a Venetian blind head-bar on said lower flange, said retainer having an inwardly-directed flange overlapping said plate in parallel relation when the retainer is in closed position, and said inwardly-directed flange having a slot extending substantially across the free end portion thereof, forming a relatively long, narrow, resilient latching tongue at the free end of said retainer and adapted to engage a portion of said flange when in closed position.

7. A bracket for supporting a Venetian blind, said bracket comprising: a plate having a projecting lower flange adapted to support the head-bar of a Venetian blind, a retainer swingably mounted adjacent to the top front corner of said plate for retaining a Venetian blind head-bar on said lower flange, said mounting comprising a pivot secured to one of said members and passing through a slot in the other of said members, material near one end of said slot being adapted to frictionally engage the other member upon sliding movement to dispose said pivot at said slot end, and means for effecting such sliding movement as said retainer is swung to open non-retaining position.

8. A bracket for supporting a Venetian blind, said bracket comprising: a plate having a projecting lower flange adapted to support the head-bar of a Venetian blind, a retainer swingably mounted adjacent to the top front corner of said plate for retaining a Venetian blind head-bar on said lower flange, said mounting comprising a pivot secured to one of said members and passing through a slot in the other of said members, material near one end of said slot being adapted to frictionally engage the other member upon sliding movement to dispose said pivot at said slot end, and means, including an extension of said retainer overlying the upper front corner portion of said plate and a cooperating cam surface projecting above the upper margin of said upper front corner, for effecting such sliding movement as said retainer is swung to open non-retaining position.

9. In a Venetian blind supporting bracket of the type in which a vertical plate is provided with a laterally-projecting blind-supporting flange and a retainer has one end thereof swingably mounted adjacent to a front corner of the plate, the retainer having an inwardly-directed flange overlapping said plate in parallel relation when the retainer is in closed position; the improvement which comprises said inwardly-directed flange having a slot extending substantially across it at the free end of the retainer, forming a relatively long, narrow, resilient latching tongue adapted to engage a complementary formation and latch the retainer in closed position.

10. In a Venetian blind supporting bracket of the type in which a vertical plate is provided with a laterally-projecting blind-supporting flange and a retainer has one end thereof swingably mounted adjacent to a front corner of the plate, the retainer having an inwardly-directed flange overlapping said plate in parallel relation when the retainer is in closed position; the improvement which comprises one of said plate and inwardly-directed flange being provided, adjacent to the swingably-mounted end of the retainer, with a lateral offset operative to set up frictional holding action between the plate and retainer, said lateral offset being inoperative when the retainer is in the initial stages of opening movement and becoming operative as the retainer approaches fully opened position.

11. In a Venetian blind supporting bracket of the type in which a vertical plate is provided with a laterally-projecting blind-supporting flange and a retainer is provided with an inwardly-directed flange overlapping said plate in parallel relation when the retainer is in closed position, said inwardly-directed flange having the upper end thereof swingably mounted adjacent to the upper front corner of the plate by a pin-and-slot connection in which the slot is downwardly inclined; the improvement which comprises the lower end of said inwardly-directed flange being inclined and, upon closing of the retainer, coacting with said blind-supporting flange to force the retainer upwardly.

12. In a Venetian blind supporting bracket of the type in which a vertical plate is provided with a laterally-projecting blind-supporting flange and a retainer is provided with an inwardly-directed flange overlapping said plate in parallel relation when the retainer is in closed position, the upper end of said inwardly-directed flange being provided with a downwardly-inclined slot pierced by a pin attached to the plate; the improvement which comprises the lower end

of said inwardly-directed flange being inclined and, upon closing of the retainer, coacting with said blind-supporting flange to force the retainer upwardly with respect to said pin.

HARRY NELSON.
